UNITED STATES PATENT OFFICE

FREDERICK W. WOOD, OF KANSAS CITY, MISSOURI.

PIANO-PLAYER.

1,152,255.

Specification of Letters Patent. Patented Aug. 31, 1915.

Application filed December 29, 1913. Serial No. 809,390.

To all whom it may concern:

Be it known that I, FREDERICK W. Wood, a citizen of the United States, residing at Kansas City, in the county of Jackson and 5 State of Missouri, have invented certain new and useful Improvements in Piano-Players, of which the following is a specification.

My invention relates to improvements in piano-players.

10 It is particularly adapted for use in ordinary upright pianos.

One of the objects of my invention is to provide, in a piano, automatic playing mechanism by which the keys will be operated 15 in a manner similar to finger manipulation.

A further object of my invention is to provide a neat and compact automatic key operating mechanism which may be easily 20 and quickly moved to a position which will leave the keys exposed for finger manipulation.

A further object of my invention is to provide a piano structure in which the key 25 cover is employed to support the automatic key playing mechanism, whereby, when the key cover is moved to the open position for finger manipulation of the keys, it will carry with it the automatic key operating mechanism, and when it is moved to the closed position it will carry the key operating mechanism into operative position.

Other novel features of my invention are hereinafter fully described and claimed.

30 In the accompanying drawings, which illustrate the preferred embodiment of my invention—Figure 1 is a front elevation, partly broken away, of an upright piano which is equipped with my improvement.

40 Fig. 2 is an enlarged, vertical sectional view, of a portion of an upright piano, equipped with my improvement, the key cover being shown in the closed position.

Similar reference characters designate 45 similar parts in the different views.

1 designates the casing and 2 a box-like key cover horizontally slidable inwardly and outwardly in side guides 3, Fig. 1, which extend horizontally inwardly and outwardly, above the black and white keys 4 and 5, with which the piano is provided, as in the usual manner. As shown in Fig. 2, the casing 1 is provided over the keys with an opening adapted to receive the key 50 cover 2.

The key cover 2 constitutes a support for

the automatic key playing mechanism. Vertically movable key operating members, 6 and 7, are disposed respectively above the black keys 4 and white keys 5, and are respectively carried and operated by the movable members, 8 and 9, of two sets of pneumatics, 10 and 11, which are respectively supported on horizontal frames 12 and 13, which in turn are carried by the key cover 2. 60

The pneumatics, 10 and 11, are operated in the usual manner and are controlled by the usual tracker bar 14, which is supported at its ends by uprights 15, which in turn are supported by a horizontal frame 16, carried by the key cover 2.

The rolls, 17 and 18, which carry the perforated music sheet 19, which co-operates in the usual manner with the tracker bar 14, are mounted on vertical posts 20, secured respectively at their upper and lower ends to the fall board 2 and frame 16. 75

The usual vacuum chamber 21, is provided in the key cover 2, and has connected to it a flexible pipe 22, which is connected to a suitable vacuum producing pump, not shown.

The pneumatics, 10 and 11, are respectively connected with the chamber 21, by the usual valved passages 23. The tracker bar 14, is also connected in the usual manner, with the vacuum chamber 21, by means of tubes 24.

When it is desired to operate the mechanism automatically, the key cover 2 is drawn 90 outwardly to the closed position, shown in Fig. 2. When the key cover is in the closed position the operating members, 6 and 7, will be in position to respectively strike those portions of the black and white keys, 95 4 and 5, which are struck with the fingers in manual playing of the piano. If, now, the music sheet 19, is operated in the well known manner, the pneumatics 10 and 11, will have their movable portions, 8 and 9, moved 100 downwardly, thereby causing the members, 6 and 7, to depress the appropriate keys, thereby automatically playing the piano.

When it is desired to manually play the piano, the key cover 2 is slid inwardly on 105 the guides 3, to a position in which it will be housed within the casing 1. At this time the keys will be uncovered for finger manipulation. For normally expanding the pneumatics, 10 and 11, the usual springs, not 110 shown, are provided.

I do not limit my invention to the struc-

ture described and illustrated, as modifications, within the scope of the appended claims, may be made without departing from the spirit of my invention.

Having thus described my invention, what I claim and desire to secure by Letters Patent is:—

1. A piano having keys, a casing, and a box-like key cover horizontally movable to a position substantially within the casing and also to a position covering the keys, and automatically operated mechanism carried by and in the key cover for operating the keys.
  2. A piano having keys, a casing, and a box-like key cover horizontally movable to a position substantially within the casing and also to a position covering the keys, and pneumatically operated mechanism carried by and in the key cover for operating the keys.
  3. A piano having keys, a casing having horizontal guides, and a box-like key cover horizontally slidable in said guides to a position substantially within the casing and also to a position covering the keys, and mechanism carried by and in said key cover for automatically operating said keys.
  4. A piano having keys, a casing having horizontal guides, and a box-like key cover horizontally slidable in said guides to a position substantially within the casing and also to a position covering the keys, and pneumatically operated mechanism carried by and in said key cover for operating said keys.
  5. A piano having keys, a casing having
- an opening above said keys and forwardly and rearwardly extending guides, a box-like support movable in said guides through said opening to a position substantially within the casing and also to a position covering the keys, and mechanism carried by and in said support and adapted to operate said keys.
6. A piano having keys, a casing, and a box-like support horizontally movable to a position substantially within the casing and also to a position covering said keys, a plurality of key operating members for respectively operating said keys carried by and in said support, and means for automatically operating said key operating members.
7. A piano having keys and forwardly and rearwardly extending guides, a support movable inwardly and outwardly on said guides to and from a position in which it will be housed in said piano, a plurality of key operating members carried by said support and disposed in positions in which, when the support is moved outwardly to a pre-determined position, they will be in positions in which they will be adapted to respectively strike said keys, and a plurality of pneumatics having means for respectively actuating said key operating members.

In testimony whereof I have signed my name to this specification in presence of two subscribing witnesses:

FREDERICK W. WOOD.
